To all whom it may concern:

Be it known that I, Aaron Braeman, a citizen of the United States, residing at Minneapolis, in the county of Hennepin and State of Minnesota, have invented a new, original, and ornamental Design for a Combination Automobile and Airplane, of which the following is a specification, reference being had to the accompanying drawings, forming part thereof.

Fig. 1 is a side elevational view of a combination automobile and airplane, showing my new design, as it appears with the wings in retracted position.

Fig. 2 is a front elevational view of Fig. 1; and

Fig. 3 is a top plan view thereof with the wings in extended position.

I claim:

The ornamental design for a combination automobile and airplane, as shown.

AARON BRAEMAN.
